UNITED STATES PATENT OFFICE

FLORENCE L. GAILEY AND JOHN K. GAILEY, OF EAGLE ROCK, CALIFORNIA

DESIGN FOR A MERCHANDISING BOOTH

Application filed June 15, 1929. Serial No. 31,721. Term of patent 3½ years.

To all whom it may concern:

Be it known that we, FLORENCE L. GAILEY and JOHN K. GAILEY, citizens of the United States, residing at Eagle Rock, in the county of Los Angeles and State of California, have invented a new, original, and ornamental Design for Merchandising Booths, of which the following is a specification, reference being had to the accompanying drawing, forming a part hereof.

The figure is a perspective view of a merchandising booth showing our new design.

We claim:

The ornamental design for a merchandising booth as shown.

Los Angeles, California, May 31st, 1929.

FLORENCE L. GAILEY.
JOHN K. GAILEY.
